INVENTOR

UNITED STATES PATENT OFFICE.

HERMAN G. PAPE, OF NEW YORK, N. Y.

DESIGN FOR A TELEPHONE-EARPIECE OR SIMILAR PHONETIC DEVICE.

53,460.

Specification for Design.

Patented June 17, 1919.

Application filed February 26, 1918. Serial No. 219,319. Term of patent 14 years.

To all whom it may concern:

Be it known that I, HERMAN G. PAPE, a citizen of the United States, and resident of New York, in the county of New York and State of New York, have invented a new, original, and ornamental Design for Telephone-Earpieces or Similar Phonetic Devices, of which the following is a specification, reference being had to the accompanying drawing, forming part thereof, in which—

Figure 1 is a side elevation of the invention as applied to a telephone receiver ear-

piece that is attached to a hand receiver shell or casing. Fig. 2 is a front elevation of the same on the line A—B of Fig. 1. Fig. 3 is a rear elevation on the line B—A of Fig. 1.

I claim:

The ornamental design for a telephone earpiece or similar phonetic device, as shown.

Signed at New York, in the county of New York, and State of New York this 25th day of February, 1918.

HERMAN G. PAPE.
